HIGHWAY SIGNAL

Jesse E. Waters, Pratt, Kans.

Application February 17, 1948, Serial No. 8,980

4 Claims. (Cl. 116—63)

1

This invention relates to a highway signal.

An object of the invention is to provide an efficient highway signal that is admirably adapted to warn motorists that they are approaching a railroad crossing.

Another object of the invention is the construction of a highway signal which can be easily discerned by a motorist in time for stopping before he crosses a railroad track in the event of the approach of a locomotive on the track.

A still further object of the invention is the construction of an efficient highway signal that can be adjusted to meet the conditions of a roadway or a highway, and which mechanism can be easily repaired.

Another object of the invention is the provision of efficient bumpers in a highway signal, which will warn the motorist in the event he does not notice the sign or signal that is part of the mechanism.

With the foregoing and other objects in view, my invention comprises certain novel constructions, combinations, and arrangements of parts as will be hereinafter fully described, illustrated in the accompanying drawings, and more particularly pointed out in the appended claims.

In the drawings:

Fig. 1 is a perspective view of a highway signal constructed in accordance with the present invention.

Fig. 2 is a view partly in side elevation, and partly in vertical section, of the highway signal constructed in accordance with this invention.

Fig. 3 is an elevated edge or end view of the highway signal.

Fig. 4 is a fragmentary, vertical sectional view of the highway signal, taken through the vertical casing thereof.

Fig. 5 is a horizontal and sectional view, taken on line 5—5, Fig. 1, and looking in the direction of the arrows.

Fig. 6 is a horizontal sectional view taken on line 6—6, Fig. 1, and looking in the direction of the arrows.

Fig. 7 is a horizontal sectional view taken on line 7—7, Fig. 2, and looking in the direction of the arrows.

Fig. 8 is a vertical, central sectional view of one of the rubber bumpers or signals.

Referring to the drawings, in which the preferred embodiment of my invention is illustrated, 1 designates a vertical, cylindrical metal casing which is mounted, or secured to, a platform 2, which platform is suitably secured upon a con-

2

crete base 3. The casing is thin, thereby saving material when constructing my invention.

5 A pole 4 fills the casing and extends down through casing 1 and into the concrete base 3, as clearly shown in Fig. 2. This pole or core 4 increases the stability and strength of the mechanism by producing a comparatively rigid support for casing 1.

The casing 1 is provided throughout its height 10 and on one side with two integral parallel flanges 5, each having an inturned lip 6, Fig. 6. By inturning the lip 6 a vertically-extending slot 7 (Fig. 6) is produced.

Near the upper end of the casing 1 and between 15 the parallel flanges 5 is mounted pulley 8, Fig. 4. A chain guide 9 is mounted on the parallel lips 5 just under pulley 8. This chain guide is provided with an eye 10 and side arms 11, Fig. 5.

Slidably mounted only between the flanges 5 20 is an elongated weight 12. The weight 12 is provided on its upper end with an eye 13 to which is secured one end of a chain 14. Chain 14 is passed over pulley 8 and then threaded through the eye 10 of the chain guide 9, extending down to easy 25 reach of the operator.

The overhanging bracket 15 of the mechanism 30 comprises an upper horizontal section 16 and a lower horizontal section 17. This bracket 15 is formed from one piece of material, such as a stiff wire or rod, and is bent into the form shown, with its inner ends preferably extending into the weight 12, whereby the overhanging bracket 15 is securely mounted upon said weight 12. The overhanging bracket 15 projects through slot 7, 35 between the inturned lips 6. A suitable sign or signal 18 may be hung upon the upper section 16, Fig. 2, or may be suspended from the lower section 17, Fig. 1. On this sign or signal 18 may be exposed any warning such as "R. R."

40 When the operator wishes to place the overhanging bracket 15 in its warning position, Fig. 1, all he has to do is to pull downward on chain 14, whereby the weight 12 is slid upwardly between the flanges 5, 5, and then by placing hook 45 19, Fig. 1, in one of the links of chain 14, the overhanging bracket 15 will be retained in its adjusted position.

To positively lock the overhanging bracket in its adjusted position, the weight 12 is provided 50 with an aperture 20, Fig. 4, and when this aperture registers with one of the sets of registering apertures 21, on parallel flanges 5, the pin 22 is inserted in these registering apertures, whereupon the weight and its overhanging bracket 15

is retained in an adjusted position, even though chain 14 is unhooked from the hook 19. The pin 22 may be bent over at one end, as shown, to prevent said pin from becoming accidentally displaced.

Rubber bumpers or signals 23 are provided, suspended from the lower section 17 (Fig. 2), with the sign 18 suspended from the upper section 16. Each rubber bumper 23 comprises a hollow rubber casing 24; in the upper end of rubber casing 24 there is mounted an anchor wire 25 which extends beyond the upper end of said rubber casing 24, Fig. 8. In attaching each rubber bumper 23 to section 17 of the overhanging bracket 15, the upper end of the bumper is laid partly around section 17 with the exposed end of the anchor wire 25 also wrapped around section 17 and pressed tight upon such section, thereby compressing part of the rubber casing, forming an excellent grip, as well as the grip obtained by the outer end of the anchor wire 25. In this novel manner of attaching, means is provided for preventing the rubber bumper from sliding along section 17; the rubber bumper is fixedly secured in the position selected by the constructor or operator of the highway signal.

As shown in Fig. 2, when the careless operator of the motor vehicle does not heed, or does not see the sign with the "R. R." thereon, then he will realize his danger by the lower ends of the rubber bumpers hitting the top or cab of the motor vehicle. These bumpers 23 will give excellent results without injury to the motor vehicle.

By reason of the adjustability of the overhanging bracket 15, repair work, as well as adjustment, can be easily obtained merely by the operator withdrawing pin 22, unhooking chain 14 from hook 19, whereupon the weight 12 will assist in lowering the overhanging bracket as the operator desires.

The mechanism being substantially constructed, by reason of employing a great amount of metallic substance in its construction, will give excellent results, as well as having a long life.

While I have described the preferred embodiment of my invention and illustrated the same in the accompanying drawings, certain minor changes or alterations may appear to one skilled in the art to which this invention relates during the extensive manufacture of the same, and I, therefore, reserve the right to make such changes or alterations as shall fairly fall within the scope of the appended claims.

What I claim is:

1. In a highway signal, the combination of a metallic casing open at both ends, a pole extending down through and filling said casing, said casing provided with a pair of outwardly-extending parallel flanges, a pulley mounted between said flanges and positioned near their upper ends, said flanges having inwardly-extending lips producing a slot there between, a chain guide mounted upon said flanges, said chain guide provided with an eye, said chain guide positioned

beneath said pulley, a sliding weight only between said parallel flanges, said weight provided on its upper end with an eye, a flexible lifting member attached to said eye of the weight and passed partly around said pulley and threaded through said eye of said chain guide, said flanges provided with sets of registering apertures, said sliding weight provided with an aperture being adapted to register with either one of the sets of said apertures on said flanges, a pin in one of the sets of apertures on said flanges and in the aperture of said sliding weight, and a signal-carrying overhanging bracket secured to said weight.

15. In a highway signal, the combination with a
concrete base of considerable depth, a platform
on said base, of a thin metallic casing, open at its
lower end upon said platform, said metallic casing
being open at its upper end, a non-metallic pole
extending through the top of said casing and
through the bottom of said casing, said pole ex-
tending at its lower end a considerable distance
into said concrete base, whereby said casing is
supported in a rigid condition, said casing pro-
vided on one side with parallel flanges, said
flanges extending to said platform, a weight posi-
tioned only between said flanges and slidably en-
gaging same, said flanges provided with sets of
registering apertures, said weight provided with
an aperture adapted to register with said sets of
registering apertures on said flanges, a pin ex-
tending through one set of apertures and through
the said aperture on said weight, and a bracket
secured to said weight and extending outwardly
beyond said parallel flanges.

35 3. In a highway signal, the combination of a
casing, a pole entirely filling said casing and ex-
tending below the bottom of said casing, said
casing provided on its side with integral weight
enclosing flanges, a weight enclosed by said
flanges and slidably engaging same, means for
40 manually adjusting said weight, and a sign carry-
ing bracket extending from said weight.

4. In a highway signal, the combination of a non-metallic pole, a concrete foundation enclosing a considerable part of the lower portion of said pole, said pole provided with a tightly fitting casing, said casing provided on its side with outwardly extending weight-enclosing flanges, a weight within said flanges only, means for manually adjusting said weight, and a sign-carrying bracket extending from said weight.

JESSE E. WATERS.
